UNITED STATES PATENT OFFICE.

CHARLES H. MOORE, OF NEW YORK, N. Y.

DESIGN FOR A TRAP-FIXTURE.

SPECIFICATION forming part of Design No. 28,268, dated February 8, 1898.

Application filed November 23, 1897. Serial No. 659,638. Term of patent 7 years.

To all whom it may concern:

Be it known that I, CHARLES H. MOORE, a citizen of the United States of America, and a resident of New York city, in the county and 5 State of New York, have invented a Design for a Trap-Fixture, of which the following is a specification.

My design for a trap-fixture is represented in side view in the accompanying drawing.

10 A is a U-shaped bottom part having on one leg of the U an end a', which in this case is shown as horizontal and threaded; but this end part is not a material part of my design. On the other leg of the U part is a ring or 15 collar a, and above this is a section B, having a straight vertical portion b, with a bent end b' at the top and a ring or collar b². Beyond this is a section C, having a straight portion

c in line axially with the bent upper end b' of the section B. The upper end of the section 20 C has a bend c', approximately vertical and with or without a ring c².

The essential features of my design are the U-shaped bottom part with the two bent sections B and C and rings a and b²; but the detailed forms of these rings may be varied.

I claim—

The design for a trap-fixture substantially as shown and described.

In testimony whereof I have signed my 30 name to this specification in the presence of two subscribing witnesses.

CHARLES H. MOORE.
